CLAIM

The ornamental design for a tie-down bracket for clamping sheet metal roll to carrier flatbed, as shown and described.

DESCRIPTION

FIG. 1 is a front elevational view of the tie-down bracket for clamping sheet metal roll to carrier flatbed showing my new design;

FIG. 2 is a top plan view thereof;

FIG. 3 is a bottom plan view thereof;

FIG. 4 is a rear view thereof;

FIG. 5 is a side elevational view thereof; and

FIG. 6 is a side elevation view.

FIG. 2

FIG. 5

FIG. 1

FIG. 4

FIG. 3

FIG. 6
